UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

SPOOL-HOLDER FOR SEWING-MACHINES.

1,219,638.

Specification of Letters Patent. Patented Mar. 20, 1917.

Application filed March 19, 1915. Serial No. 15,525.

To all whom it may concern:

Be it known that I, GEORGE S. HILL, a citizen of the United States, residing at Strafford, in the county of Strafford and State of New Hampshire, have invented certain new and useful Improvements in Spool-Holders for Sewing-Machines; and I do hereby declare the following to be a full, clear, and exact description of the invention, such as will enable others skilled in the art to which it appertains to make and use the same.

The invention relates to spool holders for sewing machines.

The object of the invention is to provide a simple and compact construction which may be used to support spools of various size and shape in the manner best suited to the size and shape of the spool, and to the kind and quantity of thread thereon. To this end the invention comprises the features of construction and combinations of parts hereinafter described and referred to in the claims.

The invention, and the advantages secured thereby, will be understood from an inspection of the accompanying drawings and the following detailed description of the spool holder illustrated therein.

In the drawings, a side elevation of a spool holder embodying the invention in its preferred form, is shown applied to the buttonhole sewing machine of Patent No. 1,063,880.

As shown in the drawings, the spool holder comprises a horizontal bracket 2 adjustably secured to a vertical rod 4 by a set screw 6. The outer end of the bracket 2 is shaped to form a spool support 8, the upper surface of which is slightly dished to receive and support a spool or thread supply indicated in dotted lines. The upper surface of the spool support may be provided with the usual felt disk upon which the end of the thread body on the spool may rest. A spool retaining rod 10 passes vertically through the center of the support 8, and extends a short distance below as well as above the support. The rod 10 is adjustably secured in position by a set screw 12. The part of the rod below the support 8 is split to form spring fingers adapted to fit within and frictionally support a small cupped spool holder 14. The spool holder 14 is provided with a central bore of such a size that when the holder is forced on to the lower end

of the rod it will be retained in position by the frictional hold of the spring fingers of the rod 10. The vertical rod 4 to which the bracket 2 is secured is bent over at its upper end, and is provided with a hook 16 arranged over the spool support 8.

In using spools or cones of certain kinds of thread, such as mercerized cotton, which are of such a character that the convolutions cling more or less to the periphery of the thread body, the thread-cone may be suspended on the hook 16, as indicated in dotted lines. This enables the thread to be drawn vertically downward from the thread supply, which is the best manner of feeding thread of this character. In using large spools or cones of thread, such as silk, which is of such a character that the convolutions readily detach themselves from the thread body, the spool or cone may be placed over the upper end of the rod 10, and be supported upon the spool support 8. In this case the thread is led from the periphery of the spool up over the hook 16 and thence to the thread guiding devices of the sewing machine. The thread is thus drawn upward from the supply, which is the best manner of feeding the thread from the usual large spool or cone. In using thread wound upon small wooden spools which have flanged ends, the spool may be placed on the lower end of the rod 10, and be supported by the cupped holder 14, in case the thread is of such a character that it is best drawn downward off of the periphery of the thread body. In the case of silk, the small spool may be placed upon the thread support 8, and thread led up over the hook 16, until the supply on the spool is so far exhausted that the thread will not draw readily off the spool when led over the hook. The spool may then be removed and placed on the lower end of the rod above the cupped holder 14, as indicated in the drawing. The thread will then draw downward off the spool and over the smooth rim of the cupped support, which will act to guide the thread and insure the proper feed of the thread to the thread guiding devices of the machine.

A spool support having the construction and arrangement above described thus provides a simple and compact structure which may be used as above indicated to meet the various conditions which arise in practice, and to support and guide the thread sup-

plies in the manner best suited to the character of the spools on which the thread is wound, and best suited to the character of the thread.

Having explained the nature and object of the invention, and specifically described one form of mechanism in which it may be embodied, what is claimed is:—

1. A spool holder for sewing machines comprising a horizontal spool support for underlying and supporting a spool, a spool retaining rod extending above and below the support, and a spool holder removably held on the lower end of the rod.
2. A spool holder for sewing machines comprising a spool support for underlying and supporting a spool, a spool retaining rod extending above and below the support and provided with spring fingers on its lower end, and a spool holder having a bore fitting the lower end of the rod.
3. A spool holder for sewing machines comprising a spool support for underlying and supporting a spool, a spool retaining rod extending above and below the support and having its lower end split to form spring fingers, and a spool holder having a bore fitting the lower end of the rod.
4. A spool holder for sewing machines comprising a vertical rod, a horizontal bracket secured to the rod and provided at its outer end with a spool support, a spool

retaining rod extending above and below the support, a spool holder removably held on the lower end of the rod, and a hook at the upper end of the vertical rod above the spool support.

5. A spool holder for sewing machines comprising a spool support for underlying and supporting a spool, a spool retaining rod extending above and below the support, and a small cupped spool holder for holding a flanged spool on the lower end of the rod.

6. A spool holder for sewing machines comprising a vertical rod, a horizontal bracket secured to the rod and provided at its outer end with a spool support, a spool retaining rod extending a short distance above and below the support and having its lower end split to form spring fingers, a small cupped spool holder having a bore to fit the lower end of the rod and adapted to be held frictionally thereon.

7. A spool holder for sewing machines comprising a vertical rod, a horizontal bracket secured to the rod and provided at its outer end with a spool support, a spool retaining rod extending above and below the support, and a spool holder removably held on the lower end of the rod.
